(57) **CLAIM**

The ornamental design for curved profile display cabinet, as shown and described.

DESCRIPTION

FIG. 1 is a front, perspective view of a display cabinet, according to an embodiment of the design.

FIG. 2 is a front view of the display cabinet of FIG. 1, according to an embodiment of the design.

FIG. 3 is a rear view of the display cabinet of FIG. 1, according to an embodiment of the design.

FIG. 4 is a left side view of the display cabinet of FIG. 1, according to an embodiment of the design.

FIG. 5 is a right side view of the display cabinet of FIG. 1, according to an embodiment of the design.

FIG. 6 is a top view of the display cabinet of FIG. 1, according to an embodiment of the design.

FIG. 7 is a bottom view of the display cabinet of FIG. 1, according to an embodiment of the design.

FIG. 8 is a front, perspective view of a display cabinet, according to another embodiment of the design.

FIG. 9 is a front view of the display cabinet of FIG. 8, according to an other embodiment of the design.

FIG. 10 is a rear view of the display cabinet of FIG. 8, according to another embodiment of the design.

FIG. 11 is a left side view of the display cabinet of FIG. 8, according to another embodiment of the design.

FIG. 12 is a right side view of the display cabinet of FIG. 8, according to another embodiment of the design.

FIG. 13 is a top view of the display cabinet of FIG. 8, according to another embodiment of the design.

FIG. 14 is a bottom view of the display cabinet of FIG. 8, according to another embodiment of the design.

FIG. 15 is a front, perspective view of a display cabinet, according to still another embodiment of the design.

FIG. 16 is a front view of the display cabinet of FIG. 15, according to still another embodiment of the design.

FIG. 17 is a rear view of the display cabinet of FIG. 15, according to still another embodiment of the design.

FIG. 18 is a left side view of the display cabinet of FIG. 15, according to still another embodiment of the design.

FIG. 19 is a right side view of the display cabinet of FIG. 15, according to still another embodiment of the design.

FIG. 20 is a top view of the display cabinet of FIG. 15, according to still another embodiment of the design.

FIG. 21 is a bottom view of the display cabinet of FIG. 15, according to still another embodiment of the design.

FIG. 22 is a front, perspective view of a display cabinet, according to yet another embodiment of the design.

FIG. 23 is a front view of the display cabinet of FIG. 22, according to yet another embodiment of the design.

FIG. 24 is a rear view of the display cabinet of FIG. 22, according to yet another embodiment of the design.

FIG. 25 is a left side view of the display cabinet of FIG. 22, according to yet another embodiment of the design.

FIG. 26 is a right side view of the display cabinet of FIG. 22, according to yet another embodiment of the design.

FIG. 27 is a top view of the display cabinet of FIG. 22, according to yet another embodiment of the design; and,

FIG. 28 is a bottom view of the display cabinet of FIG. 22, according to yet another embodiment of the design.

The broken lines shown are for illustrative purposes only and form no part of the claimed design.
